HYDRAULIC MOTOR HEAD LIFT

William H. Beretish, Chicago, Ill., assignor to
Stewart-Warner Corporation, Chicago, Ill., a
corporation of Virginia

Application September 17, 1941, Serial No. 411,108

8 Claims. (Cl. 29—84)

My invention relates to hydraulic motor head lifts adapted for raising the removable head of an internal combustion engine, or for other similar purposes.

The modern internal combustion engine usually has a removable head which is secured to the motor block by a multiplicity of studs screwed into the block and extending through openings in the head. These heads are commonly made of aluminum and frequently become so bonded to the projecting studs of the motor block that great force is necessary to remove the head and sometimes, by present methods, it is even necessary to destroy the head in order to remove it.

Sometimes the studs attached to the motor block are not exactly perpendicular to the meeting phases of the head and block so that a relatively large force is required to overcome the frictional resistance between the head and studs, whether the head be formed of aluminum, cast iron or other suitable material.

At present, there are no adequate tools for lifting, without hinges, motor heads which are difficult to remove from motor blocks and an object of my invention is to provide such a tool.

Another object of my invention is to provide a tool which may be operated by the lubricant compressors forming part of the ordinary equipment of every garage and service station.

Another object of my invention is to provide a motor head lift which can be readily operated by one hand and which will fit into very close quarters.

Another object of my invention is to provide a motor head lift which will produce a lifting force of several tons with a very slight manual effort.

Another object of my invention is to provide a motor head lift which is hydraulically operated.

Another object of my invention is to provide a motor head lift which can be either manually or power operated.

Another object of my invention is to provide a motor head lift which may be made of a few relatively simple and inexpensive parts.

Another object of my invention is to provide a motor head lift which may be readily applied to motors of different sizes and designs.

Other objects and advantages will become apparent as the description proceeds.

In the drawings:

Fig. 1 is a perspective view of a preferred embodiment of my invention applied to a motor;

Fig. 2 is a vertical section through the motor head lift shown in Fig. 1;

Fig. 3 is a vertical section through a modified form of my invention;

Fig. 4 is a vertical section showing the manner in which the supporting legs are mounted on the motor block studs;

Fig. 5 is a vertical section showing the manner in which the upper ends of these legs are attached to the base of the hydraulic lift;

Fig. 6 is a perspective view of one of the attaching clip; and

Fig. 7 is a fragmentary view showing a modification of Fig. 3.

Referring particularly to Figs. 1 and 2 of the drawings, it will be seen that I have provided a hydraulic motor head lift comprising in general a base 10 mounted on three legs 12 and carrying a cylinder 14. Each leg 12 consists of a pair of telescoping members 16 and 18 having knurled manual gripping surfaces 20 and 22, respectively. The telescopic portions 16 and 18 are threadedly connected as indicated at 24, whereby rotation of one section with respect to the other will lengthen or shorten the leg, there being sufficient friction between the threads to retain the two portions of the leg in adjusted position.

The upper section 16 of each leg is provided with an annular groove 26 (Fig. 5) for receiving the bifurcated end 28 (Fig. 6) of a spring clip 30 which serves to secure the upper end of the leg to the base 10 while my hydraulic lift is in operative position.

The lower end 32 of the lower portion 18 of each leg preferably has a diameter the same as or less than the diameter of the studs 34 which normally hold the motor head 36 in place on the motor block 38. As best shown in Fig. 4, I preferably place a sleeve 40 over each of the three studs 34 selected to support my hydraulic lift. These sleeves are of such length as to maintain alignment between the lower ends 32 of the legs and the studs 34 on which they are supported so that the motor head, as it is lifted, may move upwardly about the lower ends 32 of the legs 12. Each sleeve 40 is provided with a C-shaped spring 41 which frictionally grips its leg 12 to prevent the sleeve from slipping off or otherwise becoming accidentally displaced from its leg.

Referring particularly to Fig. 2, it will be seen that the cylinder 14 comprises a sleeve 42 threadedly secured to a head 44 which, in turn, is threadedly attached to the base 10. A piston 46 is reciprocally mounted in the cylinder 14 and is provided with a piston rod 48 extending down-

wardly through the head 44 and base 10. The head 44 has a recess in which is located packing 59 pressed firmly against the piston rod by nut 52.

The piston 46 is provided with a manually operated release valve indicated generally by reference numeral 51 and comprising a body 53 threaded into the upper end of the piston rod 44 and having a passage 55 communicating with a similar passage 57 in the upper end of the rod 43. The passages 55 and 57 constitute a by-pass around the piston 46 and this by-pass is controlled by the manually operated valve member 59. A spacing washer 61 is clamped between the piston 46 and a shoulder in the rod 43 and prevents the piston and rod from being pulled down far enough to close the lower end of the passage 57.

A block 54 is pivotally attached to the lower end of the piston rod 43 by a removable pin 56. I preferably attach this pin 56 to the block 54 by a chain 58 to prevent loss of the pin. The block 54 has an opening for receiving a draw bar 60 which may be removably secured in the block 54 by manually operated clamp 62 (Fig. 1).

A pair of heads 64 is slidable lengthwise of the bar 60 and may be secured in adjusted position by clamps 65 which are similar to the clamp 62. Each head 64 has a threaded nipple 67 for receiving one end of a spark plug adaptor 68. The lower end of each adaptor 68 has a threaded lower end 70 of a size suitable for screwing into the spark plug openings in the motor head. The adaptors 68 are preferably given a hexagonal shape and made of such length that they extend well above the motor head in order that they may be screwed into and out of the spark plug openings by the usual wrenches. In use, the spark plug adaptors with the heads 64 attached thereto are first screwed firmly into the spark plug openings. The heads 64 are then adjusted to align the openings therein with the opening in block 54 so that the bar 60 can be inserted.

Fluid is admitted to the cylinder 14 beneath the piston 46 through a pipe 72 threaded or otherwise attached to the cylinder. In the embodiment shown, a nipple 74 of a kind now commonly used in the lubrication of bearings is screwed into the inlet end of the pipe 72. Fluid is discharged from the cylinder 14 by opening the manually controlled valve 59, which immediately relieves the pressure below the piston 46, and after the motor head lift has been removed from the engine, the piston 46 and piston rod 43 can be pulled or worked downwardly, thereby causing the fluid beneath the piston to flow through by-pass passages 55 and 57 and into the space above the piston 46.

I preferably provide the cylinder with a pressure release valve 76 which has the usual spring-pressed valve member, not shown. It will be understood by those in the art that this spring-pressed valve member is set to raise from its seat whenever the pressure in the cylinder 14 reaches the predetermined maximum for which the pressure release valve is set.

The piston 46 may be raised by gas, liquid, or semi-liquid medium, although I have found it preferable to raise this piston by means of grease or oil supplied by the usual lubricant compressor forming part of the equipment of every service station and garage. In Fig. 1, I have illustrated a manually operated compressor 80 of a kind commonly used in the lubrication of bearings. This compressor comprises a reservoir and pumping mechanism whereby grease from the reservoir is discharged through a conduit 82 to a nozzle or coupler 84 which may be detachably connected to

the nipple 74 while the compressor is operated to force the grease into the cylinder and raise the piston 46 and the motor head connected thereto. After the head has been raised sufficiently, the compressor 80 may be readily detached from the nipple 74.

In lieu of the manually operated compressor 80, a power operated lubricant compressor or air compressor, or any other source of gas, liquid, or semi-liquid, either manually or power operated, may be used. In operating high motor head lifts, however, I have found it important that the piston 46 be raised in small increments and where sources of fluid pressure other than the manually operated compressor 80 are utilized, care must be exercised to prevent the piston 46 from being raised too great a distance at any one movement.

In removing a motor head from the cylinder block my motor head lift is preferably applied to one end of the head. In a preferred form of my invention, the piston 46 is given a diameter of three inches so that the piston will be lifted approximately one-thirty seventh of an inch for each stroke of the handle of a lubricant compressor of the type indicated in Fig. 1 of the drawings. Such compressors are made to provide different maximum lubricant pressures, but all of these compressors are capable of developing at least 1,200 pounds per square inch of lubricant pressure and this multiplied by the area of a three inch piston will give a total lifting force of 7,800, or approximately four tons. I have found that this force is adequate and in this particular embodiment of my invention the pressure release valve 76 has been set to open at 1,200 pounds per square inch fluid pressure.

On the first stroke of the lubricant compressor which is effective to raise the piston 46, there will be a slight bend in the draw bar 60 where the head is particularly difficult to remove. If the cylinder head is then tapped with a mallet adjacent the spark plug holes to which the tension members 68 are attached, the head will usually crack loose from the motor block. Sometimes it is necessary to operate the lubricant compressor for a second, third or fourth stroke and tap the cylinder head for each stroke before it breaks free from the motor block. If the motor head lift is in proper alignment, this operation will not result in breakage of any parts, because the pressure release valve will relieve the lubricant pressure before a dangerous point is reached.

The motor head should not be lifted more than one-sixteenth of an inch with the tool in one position. Starting at one end of the motor head the tool should be successively shifted from end to end of the motor head until the motor head has been completely separated from the motor block and has been lifted sufficiently so that it may be readily removed by hand.

While I have described the procedure which is followed in removing a motor head where only a single motor head lift is utilized, it is to be understood that under some conditions it may be desirable to apply two tools at the same time to opposite ends of the motor head. One man can remove the head of the motor in both instances.

In the modification of Fig. 3, I have shown an embodiment of my invention which incorporates a fluid reservoir and manually operated pump or compressor as a unitary part of the hydraulic lift. In this embodiment of my invention, I provide a base 110 adapted to be supported on

legs such as the legs 12 of the previous embodiment. A cylinder 112 is threadedly secured to the base 110 and carries a cap 114 which closes the upper end of the cylinder. A piston 116 is reciprocally mounted in the cylinder 112 and is adapted to be raised by a fluid forced therebeneath by pumping mechanism carried by the cap 114. The piston 116 is returned by a spring 118.

The piston 116 is provided with a piston rod 120 extending through an opening of the base 110. Packing 122 pressed against the rod 120 by gland nut 124 prevents leakage around the piston rod. The piston rod 120 is illustrated as having its lower end threaded, as indicated at 126 so that the piston rod may be screwed directly into the spark plug opening of a motor head. This arrangement, however, is less desirable than the adjustable draw bar type of connections between the piston rod 48 of the previous embodiment and the spark plug openings of the motor head, and it will be understood that the piston rod 120 may be provided with a similar draw bar type of connection. This is shown in Fig. 7, wherein, the piston rod 120' corresponds to the piston rod 120 of Fig. 3 and has attached thereto the block 54 for receiving the draw bar 60.

The cylinder 112 is adapted to be filled with water, oil, or other suitable liquid which is circulated by the pumping mechanism carried by the cap 114. This pumping mechanism comprises a plunger 128 reciprocal in a vertical bore in the cap 114 and operated by a handle 130 pivotally attached to the plunger 128, and also pivoted to the upper end of a link 132 whose lower end is pivoted to the cap 114, as indicated at 134. Packing 136 and gland nut 138 prevent leakage around the plunger 128.

Upward movement of the handle 130 and plunger 128 serves to withdraw liquid from the upper end of the cylinder 112 through conduit 140 past check valve into the lower end of the cylinder bore 144. The following downward movement of the handle and plunger forces this fluid past check valve 146 and through duct 148 to the space beneath the piston 116, thereby raising the piston and the motor head attached thereto. Reciprocation of the handle 130 is continued until the motor head has been elevated the desired amount. As in the previous embodiment, the hydraulic lift is shifted from end to end of the motor head during the complete operation of removing the head from the cylinder block.

The fluid beneath the piston 116 is returned to the upper part of the cylinder 112 by manually opening the valve 150 controlling the by-pass port 152. The valve 150 has a threaded stem mounted in a removal plug 154 and this valve has a sealing part 156 which is reciprocably mounted on a threaded stem and which is urged into sealing engagement with the walls of the by-pass 152 by a spring 158, whereby this valve constitutes a pressure release for relieving pressure beneath the piston 116 when this pressure reaches a predetermined maximum.

During the pumping operation which raises the piston 116, air is compressed in the cylinder above this piston and I have illustrated an air release valve 160 comprising a pin 162 normally urged by a spring 164 into sealing engagement with a shoulder 166 in a passageway 168 in the head 114. The spring 160 rests against a sleeve 170 threaded into the upper end of the

passage and the pin 162 is provided with a button 172 which may be manually lifted to raise the pin 162 from its seat. When the pin 162 is raised from its seat either by manipulation of the button 172 or as a result of air pressure created in the upper end of the cylinder 112, there is sufficient clearance between the walls of the passageway 168 and the pin 162 to permit escape of air therebetween. The primary purpose of this air release valve is to provide means which will permit release of air pressure in the upper end of the cylinder but will seal sufficiently tight to prevent the escape of oil or other fluid from the cylinder when the tool is laid upon its side.

My invention is adaptable without change to motors having various spacings of studs and various spacings of spark plug openings in the motor head. My invention can be readily adapted to motors having different diameter studs by using legs having different diameter lower ends, or by simply substituting other lower sections 18 in the individual legs.

Similarly, different adaptors 68 may be used to accommodate spark plug openings of different sizes. Where the lower end of the piston rod is screwed directly into the spark plug opening, as in Fig. 3, an adaptor may be interposed between the piston rod and spark plug opening to accommodate different sized openings.

The reservoir type of pump of Figs. 3 and 7 is more expensive but is cleaner and quicker to operate than the embodiment of Figs. 1 and 2, since in the latter embodiment it is necessary to empty the cylinder of grease after each use and to dispose of such grease.

While I have illustrated only two embodiments of my invention, it will be understood that my invention may assume numerous forms and that the scope of my invention is defined by the following claims:

I claim:

1. A motor head lift comprising a base, means for supporting said base from a motor block, said base having a flange and said means including a plurality of legs and a spring clip for each leg adjustably engaging said flange, a member attachable to a motor head, and means mounted on said base for lifting said last-named member and a motor head attached thereto.

2. A motor head lift comprising a base having a circular flange, a plurality of supporting legs adapted to rest on studs attached to a motor block, spring means for detachably connecting said legs with said flange and to permit adjustment of said legs relative to said flange to accommodate different arrangements of studs, sleeves carried by said legs for telescoping over said studs, a rod adapted to be moved relative to said base, means on said base for moving said rod, a block pivotally and detachably connected to said rod, a crosshead slidable in said last-named block, a pair of heads slidable on said crosshead, and means for detachably connecting said last-named heads to the spark plug openings of a motor head.

3. A motor head lift comprising a base, legs for supporting said base on studs attached to the motor block, pulling means mounted on said base, means connecting said pulling means to a motor head for raising the same, said connecting means comprising a block attached to said pulling means, a cross head slidable in said block, a plurality of pulling heads slidable on said cross head, and a member associated with each of said pull-

ing heads for attaching the same to said motor head.

4. A motor head lift comprising a base, legs for supporting said base on studs attached to the motor block, a plurality of pulling heads adapted to be screwed into the spark plug openings of a motor head, pulling means mounted upon said base and including a pull rod, an elongated member extending transversely to said pull rod, means mounting said members for bodily rotation on said pull rod on an axis transverse thereto, and means slidably securing said pulling heads to said transversely extending member.

5. A motor head lift for removing a motor head normally secured to a motor block by studs, said lift comprising a base, legs for supporting said base on said studs, means loosely securing one end of each leg to said base, sleeves slidable on the other end of each of said legs and adapted to telescope over said studs to align said legs and studs, means for preventing displacement of said sleeves from said legs, pulling heads attachable to said motor head, and pulling means mounted on said base and connected to said pulling heads to raise said pulling heads and a motor head attached thereto.

6. In a motor head lift, the combination of a base, a plurality of legs for supporting said base on motor block studs, each leg comprising a pair of relatively movable parts to permit lengthening and shortening, a sleeve adapted to fit over each leg and its adjacent stud for holding each leg in alignment with its stud, a U-shaped spring connected to each leg and adapted to clip on said base for detachably connecting each leg with said

base, a power mechanism mounted on said base and provided with a power-operated rod, a block connected to said rod, a transverse rod adjustably mounted in said block, a pair of heads adjustable lengthwise of said transverse rod, means for connecting said heads with spark plug openings of a motor head, and means for controlling said power mechanism to raise said rod and motor head.

10 7. A motor head lift comprising a circular base, legs for mounting said base on a motor block, a U-shaped spring adapted to clip on said base, said spring having a bifurcated end for detachably connecting the same to a leg whereby said spring may connect a leg with said base at any point about the periphery thereof, pulling mechanism carried by said base, means for connecting said pulling mechanism with a motor head, and means for operating said pulling mechanism to raise a motor head attached thereto.

15 8. A motor head lift comprising a base, legs for supporting said base on studs attached to the motor block, at least one of said legs comprising a pair of telescopic members movable relative to each other to vary the length of said leg, a plurality of pulling heads adapted to be screwed into the spark plug openings of a motor head, pulling means mounted upon said base and including a pull rod, an elongated member extending transversely to said pull rod, means mounting said member for bodily rotation on said pull rod on an axis transverse thereto, and means slidably securing said pulling heads to said transversely extending member.

35 WILLIAM H. BERETISH.
